(57) **CLAIM**

The ornamental design for a rechargeable battery as shown and described.

DESCRIPTION

FIG. 1 is a front, left and top perspective view of a rechargeable battery showing my new design;

FIG. 2 is a rear, right and bottom perspective view thereof;

FIG. 3 is a left view thereof;

FIG. 4 is a right view thereof;

FIG. 5 is a front view thereof;

FIG. 6 is a rear view thereof;

FIG. 7 is a top view thereof;

FIG. 8 is a bottom view thereof;

FIG. 9 is an enlarged view of a portion labeled as 9 on FIG. 2;

FIG. 10 is an enlarged view of a portion labeled as 10 on FIG. 2; and,

FIG. 11 is an enlarged view of a portion labeled as 12 on FIG. 7.

The long dash—short dash broken lines depict enlargement boundaries that form no part of the claim. The evenly broken lines illustrate portions of the article that form no part of the claimed design.
